ROD MILL

Kálmán Z. Huszár, North Indian Hill, Ohio

Application July 20, 1949, Serial No. 105,739

13 Claims. (Cl. 241—171)

1

My invention relates to an improved rod mill for crushing, pulverizing or mixing materials such as dye, face powder or the like.

A principal object of my invention is to provide novel means for at one time aiding in the recirculation of material within the rod mill, and at another time to aid in the discharge of such material from the mill.

Another object of my invention is to provide means for recirculating material within the mill, and also for discharging such material from the mill, which means may be fixed to the rod mill, said means not requiring further adjustment or interchanging of parts.

A further object of my invention is to provide improved recirculation and discharge means for handling moist or sluggish material.

Still another object of my invention is to provide a combination recirculation and discharge means for rod mills which is easy to manufacture and easy to use, thus resulting in a saving in manufacturing costs and operating time.

Other objects and advantages of my invention will become apparent during the course of the following description, and examination of the attached drawings in which like numerals are used to designate like parts throughout the same, and in which:

Figure 1 is a side elevation of a rod mill embodying my improvement;

Figure 2 is an end elevation of my improved rod mill as seen from the left of Figure 1;

Figure 3 is a section on the line 3—3 of Figure 2;

Figure 4 is a section taken on the line 4—4 of Figure 2;

Figure 5 is a view similar to that of Figure 2 but showing the device in its recirculation operation;

Figure 6 is a view similar to that of Figures 5 and 2, but showing the device in its discharge operation, and

Figure 7 is a view generally similar to Figure 5 but depicting further modifications of my invention.

Referring first to Figure 1, there is indicated at 10 a rod mill which is rotatably supported in a bearing 11 and standard 12 at its one end, and which is supported at its other end by means of a pair of rollers 13, said rod mill being provided with a metal strip or the like 14 for this purpose. The standard 12 and rollers 13 may be supported in any suitable manner from a base structure generally indicated at 15. The mill 10 is provided with a plurality of conventional rods or

2

pulverizing units indicated at 16 in Figures 3 and 4, and it is also provided with an opening by means of which the mill may be charged with material to be ground and mixed. As shown in

Figure 1 this opening is provided with a conventional, removable cover member 17.

Fixed at one end of the rod mill 10 is a ring gear 18. A driving pinion 19 carried by a shaft 20 meshes with the gear 18 and thereby serves to drive the mill 10. A pinion and shaft 19—20 are driven by means of a suitable motor indicated at 21, conventional coupling being made to a standard variable speed and reversing unit indicated generally at 22.

As best seen in Figures 3 and 4 the left end of the mill 10 is provided with a closure plate 23. A pair of openings 24 and 25 are provided in the side walls of the mill 10 adjacent the closure plate 23. The closure plate 23 is provided with a centrally located opening 26.

Fixed to the mill 10 is a recirculation and discharge conduit means which may comprise a pair of radially disposed housings 27 and 28 joined together by a suitable section 29. This

arrangement may, of course, be varied; e. g., the housings may be joined together directly, or even formed of one integral unit. These housings comprise generally U-shaped units having their side walls fixed to the plate 23 and having end flanges 30 and 31 which may be welded or otherwise secured to the outer wall of the rod mill 10. As best seen in Figures 3 and 4, the openings 24 and 25 are located between the closure plate 23 and the juncture of the mill 10 with the flanges 30 and 31, these openings and flanges thus comprising communicating passages between the housings 27 and 28 and the rod mill 10.

As best seen in Figures 2 and 4, a baffle or separator plate 32 is fixed to the closure plate 23 so that it extends longitudinally of the housings 27, 28 and divides the opening 26 into two parts. The housing sections 27, 28, and 29 are so formed as to provide an opening 33 corresponding to the opening 26 and located just opposite it, as best seen in Figure 3. The baffle 32 just nicely fits between the closure plate 23 and the outer walls of housings 27 and 28. This baffle is of sufficient length to extend beyond the openings 26 and 33 and into the housings 27 and 28.

As best seen in Figures 2 and 4, a pair of guide plates 34 and 35 are fixed at their one longitudinal edge to the baffle 32 and at their other such edge to a side wall of the central housing section 29. At their ends these guide members are fixed to the closure plate 23 and to the outer wall of one

of the housings 27-28. Thus it will be seen in Figure 4 that the guide plate 35 extends from the plate 23, at the upper edge of the opening 26, to the juncture of the housings 28 and 29, the lower edge of the opening 33. Similarly the guide plate 34 extends from the plate 23 at the lower edge of the opening 26, to the juncture of the housing members 27 and 29, the upper edge of the opening 33. These members 34 and 35 are thus located on either side of the baffle 32 in such a manner as to form a cross or X when viewed in cross-section as seen in Figure 4. Any suitable discharge device may be attached to the above described conduit means by means of the ring member 36 which is fixed thereto.

The operation of my device will now be described. Material which is pulverized or otherwise mixed in the rod mill 10 is discharged through the openings 24 and 25 into the conduit means, the rod mill being rotated in either one direction or the other. Considering Figure 5 and assuming clockwise rotation of the rod mill 10 as viewed in that figure, and as indicated by the arrow 31, there is shown my device when used to recirculate the material discharged from the rod mill 10 into the housings 27 and 28. When the rod mill 10 is in the position shown in Figure 3, material is discharged from the mill 10 through the passageway 25 and into the housing 28. As the mill 10 continues clockwise rotation, the housing 28 moves up to the position shown in Figure 5. As the housing 28 moves from the position of Figure 3 to that of Figure 5, the material which has collected in the bottom of the housing gradually shifts in position so that it is carried by the side body wall of the housing 28. As the mill continues its rotation, this material will slide down the side body wall of the housing 28 between such body wall and the baffle 32 and will fall upon the guide plate 35 and be directed back into the rod mill 10 through that portion of the opening 26 which cooperates with the guide plate 35. I have indicated the path of travel of such material by the dotted arrows in the Figure 5. It will be readily observed from this last mentioned figure that as the housing 27 follows the housing 28 in clockwise direction, material discharged from the opening 24 into the housing 27 will be carried by the bottom of this housing and later by its side wall, to such position that this material will fall down between the body wall of the housing 27 and the baffle 32 in the same manner as has just been described in connection with the housing 28. Thus this material will fall upon the guide plate 34 and likewise be directed back into the rod mill 10.

When it has been determined that further mixing is no longer desired, but rather that it is desired to discharge the now pulverized and mixed material from the mill 10, the direction of rotation of the mill is reversed. By this simple expedient of changing the direction of rotation of the rod mill 10, the pulverized material will be discharged from the mill. An examination of Figure 6 will show this to be true. Thus as the material is discharged from the mill 10 and into the passage 25 and into the housing 28, such material is carried by the bottom of the housing 28, and later its side walls, until the housing reaches such position that the material will fall between the body wall of the housing 28, and the baffle 32. Such material will strike the guide plate 34 and will be discharged from the mill via the opening 33. The path of such material is indicated by the series of arrows in Figure 6.

some of these arrows being shown in dotted lines to thus indicate material which is within the housing and the other of such arrows being in solid lines, indicating that the material has emerged into sight as seen in that figure, and as would be the case when it is discharged from the mill 10. In similar manner continual counter-clockwise rotation of the rod mill 10 will bring the housing 27 to that position indicated for the housing 28 in Figure 6. Thus, material will be discharged from the rod mill 10, through the opening 24, into the housing 27 and will be carried by the bottom of the housing 27 and then by the side body wall of such housing until such time that the material will fall by gravity between the body wall of the housing 27 and the baffle 32. This falling material will strike the guide plate 34 and be discharged through that portion of the opening 33 which cooperates with the guide plate 34.

It should be thus noted that I have provided a simple device by means of which material may be either discharged from the rod mill 10 or recirculated back into the rod mill 10 by the simple expedient of changing the direction of rotation of this mill. Such an arrangement may be easily and cheaply manufactured, and it is one which saves a great deal of time in that there are no parts which must be interchanged or adjusted when it is desired to switch from the recirculation operation to the discharge operation.

Referring now to Figure 7, there is shown modifications of the basic invention which I have just described. One of these modifications is that the side walls of the housings 27 and 28 may be of arcuate shape. I have found that in the mixing of moist or sluggish materials there is a tendency for such material to be carried too far before dropping by gravity between the side walls of the housings and the baffle plate 32. If, however, I form the housing as indicated in Figure 7, such material will start its downward movement at an earlier point in its rotation. A comparison of Figures 7 and 5 will show that this is clearly so. It should be observed, however, that although I am able to start the material to fall sooner by means of the arcuate shaped housing members, I do so at a sacrifice of the velocity of drop of the material as compared to that obtained by the use of the straight sided housing members shown in Figure 5.

Another modification of my invention is also shown in Figure 7, and this is the fact that the baffle 32 does not have to be located so that it bisects the housings 27 and 28 as is shown in Figure 5, for example. Thus this baffle 32 may be positioned in a slant position, or, similarly it may be curved as is shown in Figure 7. This allows more room between the side walls of the housing and the baffle plate, i. e. it provides a larger passage in which the material may drop back into the mill 10, that is, clockwise rotation of the rod mill 10. By the same token, however, this will allow less room between the side wall members of the housings 27 and 28 and the baffle 32 when the mill is rotated counter-clockwise in the discharge operation. In spite of this latter fact, however, such an arrangement is valuable because as a practical matter it is commonly the practice to rotate the rod mill at much higher speeds during the recirculation operation than are used during the discharge operation. It is therefore better to have a greater passageway for the material to follow in re-entering the mill 10. The reason for this is that greater

speeds of rotation of the rod mill will tend to cause the material to be carried farther around the path of rotation before it will be caused to drop by gravity through the passageways provided. Since the speeds of rotation for the discharge operation are slower, there is not this tendency for the material to be carried too far, and therefore it is not necessary that there be such a wide channel. Although I have shown both of these modifications, that is the curved-sided housings and the slanted or curved baffle as combined in the same unit, it should be noted that either one of these improvements may be incorporated in the basic invention shown in Figures 1 to 6. By that I mean it is obvious that the straight-sided housings 27 and 28 could be used in connection with a curved or slanted baffle 32 and it is equally obvious that the curved-sided housings 27 and 28 could be used in connection with a baffle 32 located in such position as shown in any of the Figures 1 to 6, rather than the curved or slanted baffle of Figure 7.

Changes and modifications may be made in my device without departing from the spirit of my invention, and I do not intend to be limited to the specific structure shown except insofar as is set forth in the subjoined claims. In this connection it should be noted that my invention may be easily adapted to use as a toy or the like by building it in miniature. The value of such adaptation lies in that my rod mill provides extremely uniform mixing coupled with easy discharge, such combination of features making my device particularly desirable for use in mixing together a plurality of numbered balls or the like and then discharging them in random order. It is thus to be understood that such adaptation—and all others embodying the use of the structural features developed by me, whether such features be made in miniature or full size—is distinctly within the scope and spirit of my invention as herein shown, described and claimed.

Having thus described my invention, what I claim as new and desire to secure by Letters Patent is:

1. In combination with a pulverizing mill including a rotatable body formed with a cylindrical side wall and opposed end walls, conduit means comprising an outermost wall and side walls, said means being fixed to said mill adjacent one of said end walls, passage means located in said cylindrical side wall for directing material from within said mill into said conduit means, said one end wall being provided with a centrally located opening, a baffle extending between said one end wall and the outermost wall of said conduit means, said outermost wall being provided with an opening substantially registering with said centrally located opening, said baffle being of substantial length relative to said one end wall and extending into said conduit means substantially centrally thereof, said baffle being so located as to divide each of said two openings into two portions, and a pair of guide plates, one at either side of said baffle and at substantially right angles thereto, each of said plates extending between said baffle and a side wall of said conduit means, one of said plates extending from the top of said centrally located opening to the bottom of said opening in the outermost wall of said conduit means, and the other of said guide plates extending from the bottom of said centrally located opening to the

top of said opening in the outermost wall of said conduit means.

2. The apparatus of claim 1 in which the side walls of said conduit means are concave.

3. The apparatus of claim 1 in which that portion of said baffle which extends into said conduit means adjacent said centrally located opening is bent away from the center line of said conduit means.

10 4. The apparatus of claim 1 in which the side walls of said conduit means are concave and in which that portion of said baffle which extends into said conduit means adjacent said centrally located opening is bent away from the center line of said conduit means.

15 5. In combination a pulverizing mill including a rotatable body formed with a cylindrical side wall and opposite end walls, a pair of radially disposed housings fixed to said mill adjacent one of said end walls, each housing comprising an outer wall and opposite side walls fixed to said one end wall, said cylindrical wall having opposed openings, passage-forming means fixed to said housings and extending outwardly therefrom,

20 25 said passage-forming means communicating with said housings and encompassing said openings, said one end wall having an axial opening, said housings being provided with an opening coaxial with said first mentioned opening, a baffle fixed to and extending between said one end wall and said outer walls, said baffle being located substantially centrally of said coaxial openings and extending longitudinally of said housings a predetermined length, and a pair of guide plates, one

30 35 fixed at either side of said baffle and substantially at right angles thereto, each of said plates extending between said baffle and a side wall of said housings, one of said plates extending from said one end wall at a position adjacent the top of said first mentioned opening to an outer wall of said housings at a position adjacent the bottom of said second mentioned opening, the other of said plates extending from said one end wall at a position adjacent the bottom of said first mentioned opening to an outer wall of said housings at a position adjacent the top of said second mentioned opening.

40 45 6. The apparatus of claim 5 in which said opposite side walls are concave.

7. The apparatus of claim 5 in which that portion of said baffle which extends into each of said housings is bent away from the center line common to said housings.

8. The apparatus of claim 5 in which said opposite side walls are concave and in which that portion of said baffle which extends into each of said housings is bent away from the center line common to said housings.

9. In a rod mill or the like comprising a cylindrical body having end walls, means for rotating said mill in either direction, conduit means fixed to said mill adjacent one end wall thereof, said conduit means comprising an outermost wall and side walls fixed to said one end wall, said one end wall having a centrally located opening, passage means leading from said cylindrical body to said conduit means and through which material passes from said mill to said conduit means upon rotation of said mill in either direction, said outermost wall having an opening substantially registering with said first mentioned opening, and a separator plate located between said one end wall and said outermost wall so as to cause material carried by said conduit means upon rotation of said mill in either direction to fall be-

50 55 60 65 70 75

tween it and the conduit side wall trailing it as said mill is so rotated, said separator plate being positioned substantially centrally of said first and said second mentioned openings and dividing each of said openings into two parts, and oppositely disposed plate means fixed at either side of said separator plate so as to divert said falling material through said first mentioned opening on one direction of rotation of said mill and through said second mentioned opening on rotation of said mill in the other direction, said plate means having a substantially X-shaped configuration as viewed in side elevation.

10. The apparatus of claim 9 in which the side walls of said conduit means are concave.

11. The apparatus of claim 9 in which that portion of said separator plate which extends into said conduit means adjacent said centrally located opening is bent away from the center line of said conduit means.

12. The apparatus of claim 9 in which the side walls of said conduit means are concave and in which that portion of said separator plate which extends into said conduit means adjacent said centrally located opening is bent away from the center line of said conduit means.

13. The apparatus of claim 11 in which the bend of said separator plate is such that there is a greater space between said separator plate and its trailing conduit side wall when said mill

is rotated in that direction in which the material falling between said separator plate and its trailing conduit side wall strikes that plate means which diverts said material through said first mentioned opening.
